UNITED STATES PATENT OFFICE

96,101

DESIGN FOR A TEXTILE FABRIC

Curt Erwin Forstmann, Montclair, N. J.

Application February 23, 1935, Serial No. 55,586

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, of which the following is a specification, reference being had to the accompanying drawing, forming part hereof.

In the drawing, the sole figure is a plan view of a piece of the textile fabric embodying the design the area bounded by the dot and dash lines indicating the repeated unit. The fabric depicted is of a single color.

The design motif is derived from wave-ripples on the sand and it consists of definite broad stripes, one extending transversely of the drawing near the top in which the convex sides of the waves face the right, another just about the middle of the drawing in which the convex waves face the left, the wave configurations between said stripes being desultorily positioned.

I claim:

The ornamental design for a textile fabric as shown and described.

CURT ERWIN FORSTMANN.
